UNITED STATES PATENT OFFICE.

HERMAN E. GOTHLBERG, JR., OF ROSELLE PARK, NEW JERSEY.

DESIGN FOR A CANOPY OR CANOPY-RING FOR LIGHT-FIXTURES.

43,609.

Specification for Design.

Patented Feb. 25, 1913.

Application filed August 13, 1912. Serial No. 714,901. Term of patent 7 years.

To all whom it may concern:

Be it known that I, HERMAN E. GOTHLBERG, Jr., a citizen of the United States, residing at Roselle Park, in the county of Union, State of New Jersey, have invented a new, original, and ornamental Design for a Canopy or Canopy-Ring for Light-Fixtures, reference being had to the accompanying drawing, forming part thereof.

In the accompanying drawing, Figure 1

is a plan view of a canopy or canopy ring showing my new design; and, Fig. 2 a side elevation thereof.

I claim;

The ornamental design for a canopy or canopy ring for light fixtures as shown.

HERMAN E. GOTHLBERG, JR.
